UNITED STATES PATENT OFFICE.

CHARLES DAVID BONSALE, OF PARNASSUS, PENNSYLVANIA, ASSIGNOR TO UNION METAL PRODUCTS COMPANY, OF CHICAGO, ILLINOIS, A CORPORATION OF DELAWARE.

CAR-WALL STRUCTURE.

Application filed August 6, 1924, Serial No. 730,430, and in Canada May 30, 1924.

Reference is had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

10 My invention has for its object to provide an all metal car construction of novel character which is unusually strong for its weight and durable throughout, which may be conveniently and economically manufactured and transported, is weatherproof and which possesses certain other desirable and advantageous features to be hereinafter described and claimed. My sheet metal wall structure is applicable to box, automobile, 15 gondola, stock or any other type of railway car equipment.

20 The ends of railway cars are subject to considerable stress due to the shifting of the lading. These blows are imparted to the end over the entire area thereof, or to local or concentrated thrust. Wheat is loaded to substantially the top of the car which causes all the blow to be imparted over the entire area of the end. Lumber is loaded to the 25 top and upon impact the top boards shift causing a blow to be imparted at the top of the end. Sand, chads and other plastic loads and light pipe cause blows at the middle of the car, whereas rail, steel plates, castings 30 and the like cause blows at the bottom of the car.

35 While, of course, efforts are made to block the lading in the car, the heavy locomotives, the emergency airbrake and the classification hump break the lading away from its moorings and throw it against the end of the car.

40 A rigid end to a car, and particularly a large box car, materially strengthens the entire superstructure to resist the torsional and weaving movements which not only rack the car to pieces, but causes leaky roofs and inoperative and leaky doors with their consequent damage claims. As it costs as much to transport a ton of freight car as it does a 45 ton of lading it is imperative that the weight of the car must be kept as low as possible, therefore, the end must be very light as well as strong. As freight cars are frequently damaged in wrecks and by other unfair

usage, any end will be damaged in service, 50 therefore, it must be capable of being easily repaired with such meager facilities as the railroads are equipped with at their outlying repair points.

In the drawings:

55 Fig. 1 shows an end elevation of a railway car with my invention applied thereon.

Fig. 2 is a section along line 2—2 of Fig. 1.

Fig. 3 is the same as Fig. 2 except that some of the panels project in different directions.

60 The usual parts of the car are shown wherein 1 is the roof; 2 the end sill; 3 the striking casting; 4 the push pole pocket and 5 the side walls of the car. The longitudinal 65 side sills, side plates, girths, center sills, ridge pole, etc., are not illustrated, as they are immaterial to the invention. Numerals 6, 7 and 8 are the middle plate and the side plates respectively of a car end wall made 70 in three pieces; however, an end wall may be made of a single plate or of any number of plates and still come within the scope of my invention.

75 Numeral 9 is the side wall of a panel 80 pressed from the main portion 10 of the plate; 11 is the side wall of a panel pressed from the elevated portion of the first mentioned panel and 12 is the side wall of a panel pressed from the elevated (or depressed) portion of the last mentioned panel. Margins 13 and 14 or 17—18 are 85 then formed between the walls.

86 In order to conserve horizontal space it 90 may be advisable to reverse the direction of some of the panels without diminishing the strength of the structure as an entirety. Suggestions along this line are shown in Fig. 3.

95 Experience has shown that the lower portion of the car end wall is subjected to greater and more frequent end thrusts than any other part thereof, therefore, it is essential that the part adjacent the floor of the car be stronger than any other part. 100 To obtain this desired result I reduce the width of the margins 15—16 adjacent the floor so that the walls at the lower edges of the panels are nearer to the floor than if the margins at the sides and bottoms of the 105 panels were maintained the same width.

Experience has also shown that a car end wall must be stronger adjacent the longitu-

dinal center of the car than adjacent the side walls. I obtain this desired result by making the margins of the panels (13—14) in the middle plate (or plates) narrower than the margins 17—18 in the plates at the side thereof. Another expedient would be to make the panels in the middle sheet or sheets deeper than the panels in the sheets on either side thereof.

10 In order to strengthen the top portion of the end wall adjacent the roof of the car I make the panels in the middle plate longer than the panels in the side plates.

15 The panels in the middle plate are preferably not only longer than the panels in the side plate but have their top walls positioned obliquely, or in other words, substantially parallel to the slope of the roof.

20 This is a continuation in part of my co-pending application Serial No. 577,035, filed July 24, 1922, now Patent No. 1,543,416, dated June 23, 1925.

I claim:

1. A sheet metal wall structure for railway cars having a plurality of sheets connected along vertical lines, each sheet having a panel embossed within a panel so as to form margins at the sides and ends of said panels, the panels in the central sheet

or sheets being deeper than the panels in the sheets on either side thereof.

2. A sheet metal wall structure for railway cars having a plurality of sheets connected along vertical lines, each sheet having a panel embossed within a panel so as to form margins at the sides and ends of said panels, the longest panel in the central sheet or sheets being longer than any panel in the sheets on either side thereof.

3. A sheet metal wall structure for railway cars having a plurality of sheets connected along vertical lines, each sheet having a panel embossed within a panel so as to form margins at the sides and ends of said panels, each central sheet or sheets provided with more panels than each adjacent sheet thereto.

4. A sheet metal wall structure for railway cars having a plurality of sheets connected along vertical lines, each sheet having a panel embossed within a panel so as to form margins at the sides and ends of said panels, the longest panel of the central sheet or sheets being longer than any panel in the sheets on either side thereof, the upper walls of said panels being substantially parallel to the slope of the car roof.

CHARLES DAVID BONSALL.
